UNITED STATES PATENT OFFICE

JOHN EDWARD THORNTON, OF LONDON, ENGLAND

MULTICOLOR CINEMATOGRAPH FILM MATERIAL

Original application filed May 5, 1924, Serial No. 711,253, and in Great Britain May 18, 1923. Divided and this application filed October 8, 1925. Serial No. 60,347.

This invention relates to a film-material for use in the production of multi-color cinematograph or other film positives in four or three colors, in which half of a picture is formed in one layer of colloid upon one piece of film and the other half of the picture in one layer of colloid on a second piece of film, each layer and each half-picture containing two colors interspersed or intermixed in close juxtaposition.

It comprises a strip of film-material of double standard width and half standard thickness, having upon its surface two stripes of colloid running side by side longitudinally of the film, each stripe formed with a mosaic pattern therein of fine lines dots or grains; the strip of material being adapted to be severed longitudinally after printing, and the images printed upon one strip being superimposed upon the images printed upon the other strip.

The invention will be fully described with reference to the accompanying drawings.

Fig. 1 is a diagrammatic section of non-reinforced film-material showing colored grains embedded in the colloid and exaggerated in size.

Fig. 2 is a view showing piece of double standard width film material with the colored grains embedded therein and the inter-spaces dyed a different color from the grains.

Fig. 3, 4, 5 and 6 are views showing lines of different colors formed in the film-material.

Fig. 7 is a perspective view of sensitized double width film-material representing a total of four colors in the double width.

Fig. 8 is a sectional view of reinforced film showing layer of reinforcing paper.

In my English Patent No. 8300, dated June 4, 1915, and United States Patent No. 1,263,962, dated April 23, 1918, I have described the manufacture of a multi-color film comprising a single support of celluloid or other material of standard thickness, upon

which was formed and secured thereto a single layer of multi-colored sensitized colloid capable of producing a multi-colored print, such print being completed in the one layer and upon the one support.

The present invention is a development of and improvement upon that invention, inasmuch that it overcomes great technical difficulties which occur when a multi-color mosaic of more than two colors is required, difficulties which render the manufacture of three or four-color material almost prohibitive in cost of production.

In the present invention these are overcome by the simple device of making the film of two parts, each of which contains only two colors, and upon a support of double the area or width but only half the standard thickness which is subsequently cut into two after printing and finishing, and after forming thereon two prints, each of which represents only half a picture, then bringing the two parts together with their two half-pictures superimposed and then cementing the two parts together to produce one film having mosaic pictures of four colors, or of three colors if desired, as described in my U. S. Patent No. 1,735,810, dated November 12, 1929 of which this application is a division.

A film-material of this improved type is not only much easier to print but yields prints of better quality; and furthermore the delicate colored images can, if desired, be enclosed and protected from scratches within the body of the film by uniting the two parts image-face to image-face; or on the other hand the two parts can be united back-to-back with their two images upon the outer faces of the film; or they can if desired be united face to back if preferred. When the parts have been cemented together the finished film-print is of standard dimensions and thickness.

By this invention half a picture comprising two component colors of a picture is formed in a fine mosaic of dots, lines or grains

in one layer of colloid upon one piece of film, and on a second piece of film in another layer of colloid the other half of the picture comprising the other two component colors is formed in a fine mosaic of dots, lines or grains, the two films, each with its half-picture, being subsequently superimposed and cemented together to produce the complete multi-color picture.

10 The film base is of any known suitable waterproof material such as celluloid or cellulose-acetate.

15 It is made in strips of double standard width and half standard thickness or approximately .002 inch thick, with a colloid coating or layer of about .001 inch thick, giving a total thickness to the film of approximately .003 inch.

20 For convenience of manufacture the thin material may be made in a broad web and when finished, afterwards slit into strips of double standard width for use.

25 If these section-films are found to be too thin and frail to withstand the rough handling of the film printery during printing, developing, and finishing, they may be strengthened by a temporary reinforcing strip of paper applied during their manufacture. In that case the film comprises transparent celluloid at the back, reinforcing paper at the front, and the multi-colored colloid layer sandwiched between.

Forming the colored layers

35 The following are different methods of arranging and manufacturing the special colloid layer of the film-material in parallel stripes in order that it will produce two section-images of different colors side-by-side in adjacent areas of the same layer or strata.

40 (A) For non-reinforced film-material the waterproof cellulose base or support is first prepared with the usual adhesive substratum known to those versed in the art of film manufacture, and is next coated with a layer of plain gelatine of about .001 inch thick, taking the thickness as being measured after drying, but it will obviously be thicker whilst wet.

45 To this gelatine layer is attached, after the gelatine has set and before it is dried, a vast number of grains of colored colloid, sufficient to entirely cover the surface of one half-width with grains of one color, and the other half-width with grains of another color.

50 The grains must be so applied that they form a single layer only one grain deep, and placed in fairly close juxtaposition so that they mostly touch each other, leaving uncovered gelatine in the spaces or angles between the adjacent grains.

55 The grains are next rolled by means of pressure rolls until they are embedded in the soft gelatine level with the surface, so that the two materials then present a common

level surface. A longitudinal cross-section of a portion of film prepared as just described is shown in Figure 1.

The colored grains may be of gelatine, starch, or similar colloid capable of being readily dyed, and are prepared by means well-known. They are either prepared with a self-mordanting dye or with an ordinary dye which is afterwards mordanted.

75 The colloid layer in which the colored grains are embedded is allowed to dry, and when dry is dyed over half width of its surface with a dye of one color and over the other half with a dye of a different color, in two longitudinal stripes, as shown in Figure 80 7, the dyes used being absorbed by the colloid layer but not by the mordanted colored grains.

85 When finished it will present a double-width material, one half of which is covered with minute areas of two interspersed colors and the other half with minute areas of two different interspersed colors, making four colors altogether as shown in Figure 2.

90 (B) According to an alternative method of manufacturing the film the film base is coated with a layer of gelatine and then dried. It is next printed with a series of exceedingly fine lines in one of the colors of mordanted dyes. When these are dry the film is next dyed in a bath of the other color, which will only enter the unmordanted and absorbent portions of the film between the already printed lines, and the latter will remain unaffected by the second color. The film will 100 then present an even layer of alternating lines of two different colors, different upon both halves, making four sets of lines in two parallel strips of four different colors, as shown in Figures 3, 4 and 5.

105 The lines of one half of the double-width film may run longitudinally, and those of the other half transversely, as shown in Figure 5, so that, when the two halves are cut and superimposed, the lines will cross and produce a pattern of squares. Or the lines of both halves may run diagonally at an angle of 45 degrees to the edge of the film, as shown in Figure 3, so that, when the two halves are cut and superimposed, the lines will cross and produce a pattern of diamonds.

110 Where the two colors cross a third color will be produced.

115 As this lineal method gives a constantly recurring pattern it is preferred to so arrange it, by making the pattern an inexact division of a complete picture area, that the mosaic pattern of dots or lines do not recur in the same place in every succeeding picture, and this arrangement, coupled with persistence of vision, obliterates on the screen any semblance of pattern or grain.

120 If preferred, fine irregularly-formed dots may be substituted for lines; or any other geometrical pattern or mosaic. But the "ac- 130

cidental" or "irregular" dot is much preferred, and in method A this result is secured automatically.

From the above description it will be clear 5 that the two images formed in different colors on each thin film strip do not superimpose, but are interspaced in adjacent areas of the same strata.

When however, the two printed films are 10 laid over each other and cemented together one two-color image will be superimposed upon the other two-color image, and, in cases where the colors overlap, other colors will be seen as a result of the combination.

15 *Arrangement of the colors*

The arrangement of the colors may be varied as desired, provided the four or three colors used produce a perfectly balanced picture. 20

No claim is made for any particular combination, but in practice the following are found to be good and convenient combinations:

25 *For a four-color picture*

Combination A.—Crimson and yellow upon one half the film, and blue and green upon the other half, as indicated in Figures 3 and 4.

Combination B.—Scarlet-red and blue-green upon one half the film, and dark-blue and light yellow upon the other half, as shown in Figure 5.

35 *For a three-color picture*

Combination C.—Red and yellow upon one half of the film and blue and yellow upon the other half, as indicated in Figure 6.

In all the above combinations the film material is intended for forming two half-pictures, each in two colors, which are sections of a complete picture; and it is intended there shall be two color-analysis made by each half 40 of the film, whether used for producing a four-color picture or only a three-color picture.

Sensitizing the colored layers

The colored film material may now be sensitized with bichromate salts for slow printing or with silver salts for more rapid printing by well known processes.

For bichromate sensitizing the film may be passed through a bath of the bichromate solution, or by applying the solution to the colloid surface with a spray, doctor-roller, or other means until the colloid is saturated with the solution, after which the film is dried and is then ready for use.

When silver sensitizing is required it may be carried out in two different ways, for example:

For a slow-printing silver film the salts of silver may be applied to the colloid layer in 65 exactly the same way as the bichromate

already described. By this means a film of the printing-out type can be made, which requires no developing. It merely requires about the same exposure as the bichromate film, then treating with the oxidizing or insolubilizing bath, and then the silver removing, as already described.

Reinforced film-material

As the film-material hereinbefore described is very thin and frail (being only half the thickness of standard film material) it may in some cases be preferred to have a stronger film that will better withstand rough handling by the operators in the film printery.

This object can be attained by manufacturing the film with a temporary backing or reinforcing strip of paper, as shown in Figure 8, which backing can be readily detached and thrown away when the film-print is complete or at any other desired stage of the finishing processes, as in my British Patent 213,647, dated December 27, 1922.

As it is necessary to print the film by exposure through the celluloid back or support, and to then develop it from the front or sensitized colloid side, these conditions must still be provided for in manufacturing the reinforced film, and such reinforced film-material is therefore constructed with the permanent celluloid support at one side, the temporary reinforcing strip of paper at the other side, and the colored colloid in the centre sandwiched between the two. The paper selected must therefore be porous in character, so that the developing and other solutions, including hot water, can readily penetrate and reach the enclosed colloid exposed layer.

Such reinforced film-material requires to be manufactured or built up in a slightly different order than the non-reinforced variety, and may be carried out by either of the following two different methods:

Method C

The celluloid base or support is first coated with the usual substratum. The porous reinforcing paper is then coated with the gelatine layer, the colored grains, spread thereon, the gelatine spaces dyed, and the whole rolled flush. Or the colored surface may be prepared according to any of the modifications A or B, already described.

After drying both the substratum on the celluloid and the colloid on the paper, the colloid surface of the latter is also coated with a substratum and dried, after which both substrata are slightly damped, laid together face-to-face, squeezed between pressure rolls, and dried. The result is a perfect and permanent union of the two strips so that they become one.

Method D

The reinforcing paper constitutes the casting base upon which the colored layer is formed. The latter is next coated with a substratum and the substratum is next coated with celluloid to form the base. When the several layers are dry the result is a film similar to that formed by method C. It is 10 a good film, but C is better.

By the addition of this reinforcement the thin material of only .00300 inch, can be brought up to about .00500 inch or more, and thus made almost as strong as standard film 15 of .00600 inch.

The invention can be applied to the production of any description of film-material upon any suitable transparent support, such as glass plates, stiff thick film-plates, thin 20 rollable films, or extremely tenuous transfer films, for producing either cinematograph or non-cinematograph multi-color positives.

What I claim as my invention and desire to protect by Letters Patent is:—

25 1. A reinforced film, including a celluloid support, a substratum carried by said support, a strip of porous paper, and a layer of colloid carried by said strip of paper, said colloid having interspersed colored areas 30 with the interspaces between said areas dyed with a different color, and said paper having its coated face attached to the substratum carried by the support and being removable from said support during the final stages of 35 development of the film.

2. The herein-described method of making a reinforced photographic film, comprising coating a support with a substratum and drying the same; coating a strip of porous paper 40 with a layer of colloid; coloring interspersed areas of said colloid layer; dyeing the interspaces between said colored areas with a different color; drying said layer; applying an adhesive coating to said colloid layer; drying 45 said adhesive coating; slightly dampening both the substratum carried by said support and the adhesive coating carried by said strip of paper; and placing the dampened surfaces of said substratum and adhesive coating together under pressure to unite them.

3. The herein-described method of making reinforced photographic film, comprising: coating a support with a substratum and drying same; coating a strip of porous paper 55 with colloid; spreading colored grains on said colloid; rolling the surface of said colloid flush and drying same; dyeing the interspaces of said colloid between said grains with another color; applying an adhesive 60 coating to said colloid surface; drying said adhesive coating; dampening both said substratum and adhesive coating; and placing the dampened surfaces of said substratum and adhesive coating together under pressure 65 sure to unite them.

4. The method of constructing a two-part mosaic colored film material for the production of multi-color positive pictures, comprising applying a layer of colloid upon a support, forming in said layer of colloid a 70 mosaic pattern in two longitudinal stripes of different colors, two colors in one stripe and two colors in the other stripe, and simultaneously sensitizing both the multi-color stripes.

In testimony whereof I have hereunto set 75 my hand.

JOHN EDWARD THORNTON.
